UNITED STATES PATENT OFFICE

2,551,168

ADHESIVE TAPE APPLICATOR

Bernard A. Rosen, Baltimore, Md.

Application January 16, 1950, Serial No. 138,868

4 Claims. (Cl. 216—30)

3

This invention relates to stationary articles and more particularly to devices for handling adhesive sealing tapes of the Scotch-tape classes, although they also can be used with tapes that are not adhesive or permanently sticky on one of its surfaces.

It has as an object the provision of a new and improved sealing tape applicator that will avoid one or more of the disadvantages and limitations of the prior art.

Another object of the invention is to provide a new and improved sealing tape applicator that can apply Scotch tape and the like in a neat and effective manner to a surface and enabling the lengths of tape to be measured off readily and as accurately as may be desired.

A further object of this invention is to provide a new and improved sealing tape applicator that will have an automatic cutter included in its mechanism as well as means for enclosing the tape when not in use, so as to keep it clean and free from extraneous mutilation.

An additional object of the invention is to provide a new and improved sealing tape applicator that will make use of parts that are operable to perform plural functions and thereby enable the device to be more effective and efficient.

While there have been tape dispensers developed heretofore, they have been limited to the extent of requiring manual ripping or cutting of the tape and in most cases the tape itself has to be dispensed entirely by hand. The handling of Scotch tape causes considerable trouble, which the present invention seeks to avoid. In the conventional method the adhesive type of tape sticks to the hands of the user and gets wound up on adjacent articles, often requiring special efforts to detach it or remove and eliminate the wrinkles that develop. This invention is a tape applicator rather than a dispenser and applies the tape in a very effective and clean manner. It dispenses the exact amount of tape required in the strip to be cut off. The cutting is done automatically and the cut is in the most effective direction. The tape does not have to be manually pressed or contacted by the operator when used, and it is always ready for additional application whenever required. The difference between a dispenser and an applicator is that the latter not only holds and delivers the tape but also acts as a device for manipulating the tape during the application.

Other objects will become apparent as the invention is more fully set forth.

For a better understanding of the invention,

its objects and the principles thereof, reference is made to the accompanying drawings. The drawings in conjunction with the following description outline the details of the device and explain its operation while the claims emphasize the scope of the invention.

In the figures shown in the drawings:

Figure 1 is a side elevation of a tape applicator embodying this invention;

10 Figure 2 is a plan view of Figure 1;

Figure 3 is a front view of Figure 1;

Figure 4 is a sectional view taken along line

4—4 of Figure 2;

Figure 5 is a sectional view taken along line

15 5—5 of Figure 2;

Figure 6 is a sectional view taken along line

6—6 of Figure 4;

Figure 7 is a perspective view showing a portion of the interior of the device, without roll

20 and knife;

Figure 8 is a sectional view taken along line

8—8 of Figure 7; and

Figure 9 is a detail in perspective of the knife used in the device and the support used for holding

25 same.

Similar reference characters relate to the same parts throughout the drawings.

In the structure indicated in the drawings, by way of example, a spool 10 is provided for insertion through the central passage of a conventional roll of adhesive tape 11. The spool enables the roll to rotate and to dispense the tape 11 as is done with the common form of rolled tape. The strip 12 pulled off the roll, is carried under a curved guide plate 13 and slides over its exterior surface. The edge portions 14 of the plate 13 are bent to form a channel that serves as a guide for the strip as it passes out of the applicator. A housing 20 centrally supports the

30 spool 10 and the plate 13 between its lateral walls 16 in any suitable manner, and is preferably contoured as shown in Figures 1, 2 and 4. The rear portion of the housing is rounded and forms a chamber 15 for the roll 11 to rotate in, and

35 the front tapers on upper and lower curved walls 30 and 31 respectively, as well as forms with the flat side walls 16 of the housing a manipulator chamber 17. The upper wall 30 of the housing has a relatively narrow open window 18 in it.

40 45 50 The lower wall 31 of the housing terminates under this window, as shown in Figure 4.

The plate 13 however continues beyond and is aligned so as to carry the strip 12 to the front face 24 of the housing and merges as a portion of the latter. Beyond that the strip 12 is free

to continue indefinitely. The plate 13 has a small window 25 under the other window 18 towards the front of the housing. This window exposes a small area of the tape 12 as it is carried to the end of the plate, and affords an opening for a knife 31 to project through.

The front portion 24 of the housing supports an arcuate cover 26 on bifurcated hinges 27 slidably journaled in the slots 19 of the lateral walls 16. Normally the cover swings under the housing and covers the area underneath the housing where the strip of tape 12 is exposed. When swung out from this position upwardly and backwardly through about 350° of an arc while at the same time adjusting it backwards in the slot 19, it will register with the wall 30 and fit its hump 21 into the window space 18. The hump 21 in this last position, contacts the cambered converging jaws 22 on the arms 33 that are pivoted at 67 and operate cutter holders 28 that support the blades 29 at right angles thereto. The complete cutter is attached to the housing by a bar 32 inserted in pockets 46, and the retracting coil spring 23 tends to keep the blades of the knife closed against each other. The insertion of the hump 21 forces the arms 33 apart when it is pushed therein, by the thumb or finger of the user. The hump 21 projects outwardly from the cover 26 and serves to balance the manipulator in a horizontal position on a table or desk, when used as a cover. When rotated backwardly to the upper position on top of the housing 20 the hump 21 fits inside the window frame 18 and projects into the housing, so its peripheral surface contacts the cambered jaws 22 and if pressed down further will spread the latter apart and in doing so also separate the blades 29 from each other. The camber of the jaws 22 resiliently resists the pressure of the hump and tends to force it upwardly, so that when the cover is released by the user, the hump and cover will rise and the blades 29 close against each other as shown in Figure 9. If a strip of tape is located along the guide plate 13 and extends through the space adjacent the blades, the tape will cut it.

The applicator is used as follows: First the operator opens the cover 26 until it rests on the upper wall 30, he presses down on the cover 26 until the blades 29 are opened and he contacts the tape at the point 45 shown in Figure 4 with the article it is to be attached to. He then tilts the applicator upwardly so the flat area 40 at the front of the housing presses firmly against the tape to evenly position it in place, and draws the applicator along the surface until sufficient tape has been applied to the selected surface. The user then lifts his thumb so the hump will rise and cause the closing of the blades by spring 23 and cause the blades to cut the strip at the edges and sever it from the balance of the tape remaining in the applicator. The cover is then swung back over the tape to enclose it. The spring 23 helps to close the blades quickly and exert the necessary pressure on the arms 33 and hump 21 to eject the latter when not impressed by the thumb of the user.

The position of the knife mechanism is preferably as indicated in the drawings. The blades 29 cut through the tape leaving the cut off strip free to be removed. The roll end portion of the strip lays on the flat faces 34 of the holders 28 and being sticky stays on them available for future use. The faces 34 are studded with projections 35 that facilitate this action and do the work. The separation of the blades permits the tape to be drawn out and applied. The slideable hinge avoids a complicated mechanism to perform its functions. One of the lateral walls 16 at the rear is split preferably at an angle at 36 and its edges bent to fit, so the cover 38 can be removable and replaceable for the purpose of renewing the roll of tape from time to time.

While but one general form of the invention is shown in the drawings and described in the specifications, it is not desired to limit this application for patent to this particular form, as it is appreciated that other forms of construction could be made that would use the same principles and come within the scope of the appended claims.

Having thus described the invention, what is claimed is:

1. A tape applying device comprising a casing housing a roll of adhesive tape and provided with an opening through which the tape is dispensed, an arcuate cover pivoted to the front of the casing and normally covering the exposed end of the tape, a pair of pivoted knives carried by said casing for cutting the tape, means for biasing said knives in noncutting position, and means carried by said cover for overcoming said biasing means and placing the knives in tape cutting position.

2. A tape applying device as set forth in claim 1, the pivot for said cover comprising a pair of trunnions extending from said cover and slideable in slots provided in the front end of said casing.

3. A tape applying device as set forth in claim 1, said pivoted knives having adjacent terminal jaws and the means for overcoming the biasing means consisting of a cam element carried by said cover and forcing said jaws apart.

4. A tape applying device as set forth in claim 1, the pivot for said cover comprising a pair of trunnions extending from said cover and slideable in slots provided in the front end of said casing, and said pivoted knives having adjacent terminal jaws and the means for overcoming the biasing means consisting of a cam element carried by said cover and forcing said jaws apart.
